[57] CLAIM

The ornamental design for a fluid processing system, as shown and described.

DESCRIPTION

FIG. 1 is a perspective view of the fluid processing system of the present invention;

FIG. 2 is a front view of the fluid processing system shown in FIG. 1;

FIG. 3 is a side view of the fluid processing system shown in FIG. 1, the opposite side view being identical thereto; FIG. 4 is a top view of the fluid processing system shown in FIG. 1;

FIG. 5 is a bottom view of the fluid processing system shown in FIG. 1; and,

FIG. 6 is a rear view of the fluid processing system shown in FIG. 1.
